UNITED STATES PATENT OFFICE.

WILLIE F. WALL, OF SAN FRANCISCO, CALIFORNIA.

PEN-POINT.

1,312,712.

Specification of Letters Patent. Patented Aug. 12, 1919.

Application filed February 11, 1919. Serial No. 276,421.

To all whom it may concern:

Be it known that I, WILLIE F. WALL, a citizen of the United States, residing at San Francisco, in the county of San Francisco and State of California, have invented certain new and useful Improvements in Pen-Points, of which the following is a specification.

This invention relates to pen points, and 10 the object thereof is to so construct such a point that piercing of the paper is prevented.

Another object of the invention is to provide a pen point having an upturned writing end or tip.

With the foregoing and other objects in view, which will appear as the description proceeds, the invention resides in the combination and arrangement of parts and in 20 the details of construction hereinafter described and claimed, it being understood that changes in the precise embodiment of the invention herein disclosed may be made within the scope of what is claimed without 25 departing from the spirit of the invention.

In the accompanying drawings:—

Figure 1 represents a perspective view of a portion of a pen holder with this improved point shown applied.

30 Fig. 2 is a plan view of the point removed, and

Fig. 3 is a side elevation thereof.

In the embodiment illustrated a pen-holder H of usual construction is shown in 35 which a pen point 1 is designed to be mounted in the ordinary manner. This pen 1 has the usual slip 2 extending through the point thereof and terminating at its inner end in a slot 3. The tip or point 4 of this pen is 40 turned upwardly and rounded to prevent piercing of the paper during the writing

operation. This upturned tip or point 4 tapers to its free end in the usual manner so that the lower face of the writing portion thereof will be wider than the upper, hence 45 when it is desired to write heavily the lower face of said rounded point is used, and to produce fine writing, the upper face is used.

From the above description it will be obvious that by so bending the tip of a pen 50 point, a substantially ball-point pen may be formed which is cheap to manufacture and will have all of the advantages of the ball-point pen now in use.

From the foregoing description, taken in 55 connection with the accompanying drawings, the advantages of the construction and of the method of operation will be readily apparent to those skilled in the art to which the invention appertains and while I have 60 described the principle of operation of the invention together with the device which I now consider to be the best embodiment thereof, I desire to have it understood that the device shown is merely illustrative and 65 that such changes may be made as are within the scope of the claimed invention.

Having thus fully described my invention, what I claim as new and desire to secure by Letters Patent, is:—

A pen having an elongated tapered point with the tip thereof turned upwardly and rounded, the terminal of said tip contacting with the upper face of the point and being narrower than the lower writing face. 75

In testimony whereof I affix my signature in presence of two witnesses.

WILLIE F. WALL.
